SIEGMUND LOEWE, OF BERLIN, FRIEDENAU, GERMANY, ASSIGNOR TO RADIO CORPORATION OF AMERICA, A CORPORATION OF DELAWARE

MULTIPLE UNIT TUBE

Application filed April 29, 1927, Serial No. 187,684, and in Germany July 19, 1926.

The present invention discloses ways and means whereby improvements in multiple-unit tubes for line connection can be carried into practice. The so-called multiple-unit tubes contain within a joint vacuous space several amplifier systems together with the requisite coupling elements, the latter consisting most generally of high-ohmic resistances and blocking condensers.

10 The subject-matter of the present invention is a multiple-unit tube specially designed and adapted for direct connection with a supply circuit or network. The chief feature of the same resides in the fact that the filaments of 15 all of the systems contained inside the multiple-unit tube are connected in series, for the purpose of being able to obtain the comparatively high negative biasing potential required for the last grid directly in the tube 20 itself, so that no distant seal and lead-in is required for the last grid. If the potential drop across the series-connected filaments is not yet sufficient, then a separate series resistance is disposed in series with the filaments, also in the tube itself. Connection 25 with the last grid is then also made inside the tube, to be more precise, with this series resistance.

A tube having this construction is illustrated in Figure 1.

The joint vacuous space 1 contains three amplifier systems. The filaments are designated by 2, 3 and 4. According to this invention, all of these cathodes are connected in series, with the result that only two lead-outs are required, an additional resistance being connected in series with the first filament 2. 5, 6 and 7 are the grids of the three stages, and 8, 9 and 10 their plates. 40 11 and 12 are plate resistances, 13, 14 grid leaks, 15, 16 coupling condensers, 17 the lead to the first grid. The current-supply lead to the first two plates is denoted by 18.

The biasing potentials are obtained in the following manner: In the case of the second grid, the leak resistance 13 is connected with the negative filament pole of the tube next below. The grid of the third tube which ordinarily is of the loud speaker terminal-stage type, and which possesses a high in-

verse amplification factor and therefore a high biasing potential (from 6 to 15 volts), of the filaments combinedly involve at least from 10 to 15 volts potential drop, are likewise connected with the negative filament 55 pole of cathode 2. If this is not the case, connection is made with the distinct series resistance 19. In this manner, a three stage tube is provided with only five connections, that is, only one connection more than the 60 ordinary tube. At the same time, this tube is particularly suited for network-connection devices and hot-cathode rectifiers with which it is comparatively easy to obtain high potentials, but only large currents with difficulty. The series arrangement of the filaments therefore makes the tube especially suited for use with network connection means, while making dispensable a separate lead-in for the grid-leak of the last stage. 70

I claim as my invention:

1. A multiple-unit tube having a plurality of stages, each stage comprising a filament, control electrode, and anode, the filaments of said stages being connected in series and a connection within the tube between the grid of one of the stages and the filament of the preceding stage for biasing the said grid. 75

2. A three-stage multiple-unit tube having a plurality of stages, each stage comprising a filament, control electrode, and anode, the filaments of said stages being connected in series, a connection between the grid of the second stage and the negative pole of the filament of the first stage for biasing the grid of the second stage, and a connection between the grid of the last stage and an impedance within the tube in series with the lead to the said negative pole. 85

3. A multi stage amplifier tube unit having 90 a plurality of multiple electrode systems, each system comprising a filament, control electrode, and anode, the filaments of said systems being connected in series; means within the tube for obtaining a biasing potential for one of said systems at the negative pole of the filament of a preceding system; and other means for taking the biasing potential for the end system off at the negative filament pole of a preceding system. 95 100

4. In a multi stage amplifier tube, a plurality of stages, each stage comprising a cathode, a control electrode, and an anode, the cathodes of all the stages being connected in series; a resistance in series with the cathode of the first stage; and connections within the tube from said resistance to the control electrodes of the intermediate and end stages of said amplifier, for supplying biasing potentials thereto.

5. A three stage amplifier tube, each stage comprising a cathode, control electrode, and anode; a resistance in series with the cathode of the first stage; a connection between one point on said resistance and the control electrode of the second stage of said amplifier for supplying a biasing potential thereto; and another connection from another point on said resistance to the control electrode of the end stage of said amplifier for supplying a biasing potential thereto.

SIEGMUND LOEWE.
